Primary Examiner — Philip S Hyder(74) *Attorney, Agent, or Firm* — Dinsmore & Shohl LLP(57) **CLAIM**

The ornamental design for a handle, as shown and described.

DESCRIPTION

FIG. 1 is a perspective view of a handle embodying my new design, wherein an associated scoop is shown in broken lines;

FIG. 2 is a top plan view of the handle;

FIG. 3 is a bottom plan view of the handle;

FIG. 4 is a left side elevation view of the handle;

FIG. 5 is right side elevation view of the handle;

FIG. 6 is an end view of the handle;

FIG. 7 is an opposite end view of the handle; and,

FIG. 8 is another perspective view of the handle.

The broken lines showing the scoop is provided for purposes of environment and forms no part of the claimed design.
